Patented Apr. 12, 1960

187,655

PLAY CLIMBER

Robert S. Wormser, Mexico, Pa., assignor to The Mexico
Forge, Inc., Mexico, Pa., a corporation of Pennsylvania

Application October 15, 1959, Serial No. 57,942

Term of patent 14 years

(Cl. D34—5)

The single figure is a perspective view of a play climber showing my new design. The essential features of the design are shown in full lines.

I claim:

The ornamental design for a play climber, substantially as shown and described.
